FENCE POST

Filed July 26, 1927

UNITED STATES PATENT OFFICE

FRANCIS L. LINDEMUTH, OF PUEBLO, COLORADO, ASSIGNOR TO THE COLORADO FUEL
AND IRON COMPANY, OF DENVER, COLORADO, A CORPORATION OF COLORADO

FENCE POST

Application filed July 26, 1927. Serial No. 208,515.

My invention relates to metal posts of the type used in building fences and the like and it is an object of the invention to provide a metal post of V-shaped section in which strength and rigidity of construction are combined with lightness in weight and practicability in use and production.

Another object of the invention is to provide in association with a post of the above-described character, efficient, strong and readily applied means for fastening the fence wires thereto, and a further object is to provide in connection with the post an improved means to securely anchor the post in the soil.

An embodiment of the invention has been illustrated in the accompanying drawings in the several views of which like parts are similarly designated and in which

Figure 1 represents a fragmentary elevation of a fence including posts, anchoring means and wire fastening devices in accordance with the present invention,

Figure 2, a fragmentary side view of one of the posts,

Figure 3, an enlarged cross-section taken on the line 3—3 of Figure 1, and

Figure 4, a cross section along the line 4—4 of Figure 1, drawn to an enlarged scale.

Referring further to the drawings, the posts 5 as shown, are made of steel, iron or other suitable material in the form of an angle bar of V-shaped section. The posts are preferably rolled to the desired shape and they are pointed at their lower ends to facilitate driving them into the ground. At the apex of the angle and lengthwise of the post is a rib or backbone 6 which may be increased in thickness with relation to the sides of the post and which is notched at its outer edge to provide seats for the wires of the fence.

The notches 8 formed in a continuous series along the face of the reenforcing rib, may be of ratchet shape and their lower ends are curved to provide rounded shoulders 9 on which, in practice, the fence wires are supported.

The shape of the notches has a particular advantage in enabling the post to accommodate various sizes of wires interchangeably as any wire regardless of size, will seat

in the lower curved portion of its notch and will not be permitted vertical play, because of the overhanging portion 8. Furthermore, a post having teeth of this shape can be economically rolled as it is not necessary to 55 redress the rolls and thus protusions for the notches may be maintained for a considerable length of time.

The means for fastening the fence wires in place in their respective seats consist of 60 wire clips 10 of V-shaped form which embrace the rib 6 of the post and which at their extremities are bent around the edges of the sides of the same.

It will be observed that the legs of the 65 clips extending across the sides of the post at an acute angle to each other, resist deformation under stress owing to a substantially straight and lengthwise tension and that therefore the clips will hold the wires securely in their seats against lateral displacement.

The rib at the apex of the angle of the post reinforces the construction and permits of 70 forming the sides of the same of comparatively thin metal, and this feature taken together with the angular shape of the post insures with less amount of weight, a post as strong, if not stronger, than other metal posts at present in use.

By reason of the ease with which a post of the described form may be rolled to a very thin section of greater over-all dimensions, the production of the post is practical and inexpensive, and owing to the fact that the 75 metal is spread over a great area, the post provides a firm anchorage when driven into the ground.

If, as occurs under certain conditions, it is desirable to provide additional anchoring 80 means, a blade of the form illustrated in Figures 1 and 3, is of practical value. The blade 12 is V-shaped in correspondence with the angle of the post. It is fitted in the angle of the post and projects beyond the edges of 85 the same to provide wings 13 that may curve around and beyond the edges to better withstand the lateral strains to which the fence of which the posts are part, is subjected 90 when in use.

The anchor is fastened in the angle of the post by rivets 14 welding or other means and the upper and lower edges of its wings are slanted to reduce resistance when the post is 5 driven in the ground.

I claim:

1. A fence post having a longitudinal rib provided with ratchet shaped notches curved at their lower ends to provide shoulders for 10 the support of fence wires.

2. A fence post having a longitudinal rib provided with a continuous series of ratchet shaped notches curved at their lower ends to provide shoulders for the support of fence 15 wires.

3. A fence post having a longitudinal rib provided with ratchet shaped notches curved at their lower ends to provide shoulders for the support of fence wires, and a clip for fas- 20 tening each wire and retaining same in the lower curved end of its respective notch.

In testimony whereof I have affixed my signature.

FRANCIS L. LINDEMUTH.
